ASH TRAY

Lula L. Dalrymple, Madison, and De Moss Dick-
son, Basco, Wis.

Application March 19, 1940, Serial No. 324,854

1 Claim. (Cl. 131—237)

This invention relates to an ash tray; and it is an object of the invention to provide an article of this kind provided with rotating members between which the stub of a cigar or cigarette is caused to pass to assure the extinguishing of such stub before the same is received within the tray proper.

It is also an object of the invention to provide a device of this kind with means whereby the same may be readily mounted upon a desired support irrespective of whether the same may be flat or substantially cylindrical.

The invention consists in the details of construction and in the combination and arrangement of the several parts of our improved ash tray whereby certain important advantages are attained and the device rendered simpler, less expensive and otherwise more convenient and advantageous for use, as will be hereinafter more fully set forth.

The novel features of our invention will hereinafter be definitely claimed.

In order that our invention may be the better understood, we will now proceed to describe the same with reference to the accompanying drawing, wherein:

Figure 1 is a view in side elevation of an ash tray constructed in accordance with an embodiment of our invention;

Figure 2 is a view in top plan of the device as herein embodied;

Figure 3 is a sectional view taken substantially on the line 3—3 of Figure 2 looking in the direction of the arrows;

Figure 4 is a sectional view taken substantially on the line 4—4 of Figure 3 looking in the direction of the arrows.

Our improved ash tray as herein disclosed comprises a container 1 of desired dimensions and formed of suitable material. This container 1 as herein embodied is substantially cylindrical in form with its top portion open at 2. This open top portion is defined by the upstanding walls 3. One of the side walls 3 at its central part carries an exterior socket member 4 herein disclosed as of a wedge type and in which is adapted to be snugly received the bracket 5 carried by and extending beyond an end portion of the long arm 6 of a substantially L-shaped member M. The short arm 7 of the member M is adjacent to the bracket 5 and this short arm 7 constitutes the upper jaw for a clamp. The long arm 6 is preferably substantially cylindrical in cross section but having its inner portion provided therealong, as at a, with a flattened face

and which flattened face is provided with a series of longitudinally spaced notches 8.

Slidably mounted upon the long arm 6 is an end portion of a clamp plate 9 and the notches 8 provide means whereby the plate 9 may be effectively maintained in desired selected position with but slight pressure upon the plate 9.

The plate 9 is disposed from the long arm 6 in the same direction as the short arm 7 and the outer end portion of the plate 9 has threaded therethrough a screw member 10, the extremities of this member 10 disposed toward the arm 7 having swivelled thereto a jaw 11. The opposed working faces of the arm or jaw 7 and the jaw 11 are provided with the grooves 12 whereby said jaws 7 and 11 may be caused to effectively engage a flat support such as the marginal portion of a table or a support substantially circular in cross section. To facilitate the proper engagement of the jaws 7 and 11 with flat surfaces, the opposed working faces of such jaws at opposite sides of the grooves 12 are flattened, as at 14.

As clearly illustrated in the accompanying drawing, the top of the container at the opposite ends thereof is closed, as at 15, but having a central opening 16. The top closed end portions 15 provide areas upon which cigars or cigarettes may be readily placed while the opening 16 provides means in which to drop ashes into the container or to drop the stubs therethrough.

Extending transversely of the upper portion of the container 1 and supported by the side walls thereof are the substantially parallel shafts 17 and 18. The mounting for the shaft 17 maintains such shaft in a fixed position while the mounting for the shaft 18 constitutes slots 19 so that the shaft 18 may have movement toward or from the shaft 17.

Mounted upon the shafts 17 and 18 are the cylindrical members or drums 20 and 21 respectively. These members or drums 20 and 21 are provided at their opposite ends with the outstanding surrounding flanges 22, the peripheries of which are in contact so that said drums 20 and 21 may be rotated in unison but, of course, in reverse directions. These flanges 22, as herein disclosed, have their peripheries roughened or serrated as at 23 to assure effective driving engagement between the members or drums 20 and 21.

The member or drum 21 is freely mounted on its shaft 18 and the extremities of the shaft 18 extend outwardly beyond the side walls of the container 1. These side walls of the container

1 adjacent to the shaft 18 are provided with the outstanding brackets 24. Interposed between these brackets 24 and the extended end portions of the shaft 18 are the expandable springs 25 which serve to constantly urge the drum 21 toward the member or drum 20 to maintain the same in driving engagement one with the other. However, these springs 25 will sufficiently yield to allow the member or drum 21 to move away from the member or drum 20 to permit the passage therebetween of a stub of a cigar or cigarette but with such stub under certain pressure to assure the extinguishing of any burning part of the stub. The member or drum 20 rotates with its shaft 17 and this shaft 17 has a portion extending beyond a side of the container 1 and to which extended portion is fixed an operating wheel 26. This wheel has extending outwardly from its periphery at points spaced circumferentially therearound the nubs or lugs 27 to facilitate the desired rotation of the wheel 26.

The peripheries of the members or drums 20 and 21 between the flanges 22 thereof are provided with the circumferentially spaced grooves or channels 28.

Depending from the inner ends of the closed top portions 15 and extending downward in convergence toward the members or drums 20 and 21 are the plates 29. These plates 29 have their lower ends terminating closely adjacent to these members or drums 20 and 21 at opposite sides of the bight thereof and between the flanges 22. As illustrated in Figure 4, the walls 3 are provided with the inwardly disposed flanges 30 which extend across the opening 16. These flanges 30 provide additional area upon which a cigar or cigarette may be supported and preferably with the ash end thereof over the opening 16.

The lower portion of one of the side walls of the container is open, as at 31, and which is normally closed by a removable door 32. As herein disclosed, this door 32 closely conforms to the opening 31 but has a marginal portion, as indicated at 33, which laps the portion of the 45

side wall adjacent to the opening 31 while the lower portion of the door 32 carries a swinging latch 34 which tightly engages the bottom wall of the container.

5 From the foregoing description it is thought to be obvious that an ash tray constructed in accordance with our invention is particularly well adapted for use by reason of the convenience and facility with which it may be assembled and operated, and it will also be obvious that our invention is susceptible of some change and modification without departing from the principles and spirit thereof and for this reason we do not wish to be understood as limiting ourselves to the precise arrangement and formation of the several parts herein shown in carrying out our invention in practice except as hereinafter claimed.

We claim:

20 An ash tray comprising a container having an opening in its top, marginal portions defining such opening providing supporting areas for cigars or cigarettes, drums rotatably mounted within the container in the upper portion thereof, one of said drums being movable toward or from the other, means coacting with said movable drum for normally maintaining the same in driving engagement with the second drum, means exteriorly of the container for rotating the second drum, the bight between the drums being below the opening in the top of the container, the end portions of the drums being provided with outstanding surrounding flanges, the flanges of one drum having direct contact with the flanges of the second drum, the peripheries of the drums between the flanges being free of contact, and plates depending from the top of the container at opposite sides of the bight between the drums and substantially bridging the spaces between the top of the container and the peripheries of the drums, said plates also extending between the flanges of the drums.

LULA L. DALRYMPLE.
DE MOSS DICKSON.
